UNITED STATES PATENT OFFICE.

BENJAMIN I. CORSON, OF MINNEAPOLIS, MINNESOTA.

FIRE-EXTINGUISHING LIQUID.

1,401,240.

Specification of Letters Patent. Patented Dec. 27, 1921.

No Drawing.

Application filed January 31, 1920. Serial No. 355,356.

To all whom it may concern:

Be it known that I, BENJAMIN I. CORSON, a citizen of the United States, residing at Minneapolis, in the county of Hennepin and 5 State of Minnesota, have invented certain new and useful Improvements in Fire-Extinguishing Liquids; and I do hereby declare the following to be a full, clear, and exact description of the invention, such as 10 will enable others skilled in the art to which it appertains to make and use the same.

My invention has for its object to provide an exceedingly cheap, yet highly efficient substance for extinguishing fires, and especially adapted to smother and extinguish flames produced by burning oil or other liquid fuel.

Various different compounds or substances have been produced for this purpose. All, or nearly all, have employed chemical substances, which, when brought together, generate carbon dioxid. Sodium carbonate and an acid, such as sulfuric acid or sodium bicarbonate and aluminum sulfate, 20 have frequently been used for this purpose.

Such compounds have also hitherto contained a third ingredient having as its function the production of a blanket of foam on the surface of the oil to facilitate in extinguishing the flames by cutting off the air supply necessary to support the combustion. As this third ingredient, soap, gum arabic, saponin, and other quite expensive materials have been used, but I have discovered an 30 ingredient or substance for this purpose which is not only better than the substances named, but is many times cheaper. The substance which I put to the above use for producing the blanket of foam is the sediment or sludge obtained as a waste by-product in 35 tanning processes known as phlobaphenes.

There are two well known processes of tanning. The one being known as the chrome process and the other as the mark or 45 tannin process, but it is from the latter, or old process that I have obtained in the waste residue or sludge, the material found so efficient for producing, in the fire extinguisher, the blanket forming foam. This tanning residue or phlobaphenes has hitherto been treated as waste and has been thrown away or disposed of in any possible way as by 50 running the same into rivers.

The fire extinguisher is made in the form 55 of two liquids which are kept separated until the time that they are to be thrown upon

the fire. I have made a highly efficient fire extinguisher by first forming two liquids, as follows:

1. Ten parts bicarbonate of soda, eighty 60 parts of water, and ten parts of sediment or sludge from the waste tanning liquid residue.

2. Ten parts of aluminum sulfate and 65 ninety parts of water.

When these two liquids are commingled, the aluminum sulfate and sodium bicarbonate generate or produce the carbonic acid gas and the tanning residue or sludge produces the blanket of foam that cuts off the 70 air and smothers the flames. The water in the mixtures acts as a carrier to distribute the fire extinguishing elements, and also serves to facilitate the generation of a carbon dioxide. This phlobaphenes forms spontaneously 75 during the mechanical process, and settles to the bottom of the vat. It contains tannin and tannin compounds but it is not generally used for tanning purposes because it is insoluble in acid or neutral solution. However, it dissolves during an alkaline solution but will not tan in such combination. However, phlobaphenes is soluble in bicarbonate of soda or in caustic soda, or 80 a mixture of the two.

This extinguisher, when thrown upon combustible materials in the vicinity of a fire will also prevent them from igniting. In practice I have found that this fire extinguishing substance, when thrown upon 90 objects, will produce a protecting blanket of foam that will last about twenty-four hours.

These two liquids or solutions are kept separate until the time it is thrown onto the fire and when they are commingled the aluminum sulfate acts on the sodium bicarbonate to produce carbonic acid gas and the tanning residue then acts as the so-called third ingredient to produce a blanket of foam which cuts off the air and smothers 100 the flames. The water in the two mixtures, simply acts as a carrier to help distribute the fire extinguisher and it facilitates the generation of a carbonic dioxid.

What I claim is:

1. A component for a foam producing fire extinguishing charge, consisting of the product produced in the tannin process of tanning known as phlobaphenes combined with a gas producing chemical substance, 110 said combination when associated with a complementary composition operating to pro-

duce fumes non-supporting to combustion and foam.

2. A fire extinguishing charge consisting of two separate solutions containing substances adapted to unite to produce fumes non-supporting to combustion, one of said solutions having mixed therewith the product resulting from the tanning process known as phlobaphenes.

10 3. A fire extinguishing charge consisting of two separate solutions containing sub-

stances adapted to unite to produce fumes non-supporting to combustion, one of which comprises a solution of sodium bicarbonate and a waste product from the tanning process comprising phlobaphenes. 15

In testimony whereof I affix my signature in presence of two witnesses.

BENJAMIN I. CORSON.
